(57) **CLAIM**

What is claimed is the ornamental design for a female dual lumen connector, substantially as shown and described.

DESCRIPTION

FIG. 1 is a front isometric view of a first embodiment of a female dual lumen connector taken from the top, right side.

FIG. 2 is a rear isometric view of the female dual lumen connector of FIG. 1 taken from the top, left side.

FIG. 3 is a right side elevation view of the female dual lumen connector of FIG. 1.

FIG. 4 is a left side elevation view of the female dual lumen connector of FIG. 1.

FIG. 5 is a rear elevation view of the female dual lumen connector of FIG. 1.

FIG. 6 is a front elevation view of the female dual lumen connector of FIG. 1.

FIG. 7 is a top plan view of the female dual lumen connector of FIG. 1.

FIG. 8 is a bottom plan view of the female dual lumen connector of FIG. 1.

FIG. 9 is a front isometric view of a second embodiment of a female dual lumen connector taken from the top, right side.

FIG. 10 is a rear isometric view of the female dual lumen connector of FIG. 9 taken from the top, left side.

FIG. 11 is a right side elevation view of the female dual lumen connector of FIG. 9.

FIG. 12 is a left side elevation view of the female dual lumen connector of FIG. 9.

FIG. 13 is a rear elevation view of the female dual lumen connector of FIG. 9.

FIG. 14 is a front elevation view of the female dual lumen connector of FIG. 9.

FIG. 15 is a top plan view of the female dual lumen connector of FIG. 9; and,

FIG. 16 is a bottom plan view of the female dual lumen connector of FIG. 9.

The broken lines shown in the drawings are for illustrative purposes only and form no part of the claimed design.
